UNITED STATES PATENT OFFICE

2,580,013

CLEANER AND HUMIDIFIER FOR
CARBURETORS

Antoine Gazda, Providence, R. I.

Application May 12, 1949, Serial No. 92,805

2 Claims. (Cl. 183—19)

1

The present invention relates to the cleaning and humidifying of the suction air for an internal combustion engine.

It is an object of the invention to provide an apparatus that will thoroughly clean the air prior to delivery to the carburetor of the internal combustion engine and that will increase substantially the water content of the air which, as is well known, increases the efficiency of the internal combustion engine.

A still further object of the invention is to provide a construction wherein due to the enlarged surface contacted by the air an increased cleaning and humidifying action is secured without increasing the overall dimensions of the device.

A still further object of the invention is to provide a compact structure which may be quickly and easily disassembled for cleaning, replacement and repair purposes.

With the above and other objects in view which will appear from the detailed description below, the invention is shown in the drawings in which:

Fig. 1 is a cross-sectional view taken upon section line 1—1 of Fig. 2, with parts shown in elevation.

Fig. 2 is a cross-sectional view on line 2—2 of Fig. 1.

Fig. 3 is a vertical sectional view taken upon section line 3—3 of Fig. 4 with parts in elevation of a modified construction, and

Fig. 4 is a cross-sectional view on line 4—4 of Fig. 3.

When a humidifier is used with an internal combustion engine the engine efficiency improves during operation if the water content of the air suctioned into the engine during the suction stroke thereof is increased. The humidifier and cleaner of the present invention increases the water content of the air approximately 300% above the yield of humidifiers at present in use by enlarging the available surface of the porous material over which the air passes prior to being suctioned into the engine.

Referring to the drawings, wherein like reference characters indicate like parts, one modification of the invention is shown in Figs. 1 and 2 wherein the humidifying and cleaning element 10 is constructed of ceramic porous material or any other porous hygroscopic material, such as powdered metal, etc.

The element 10 is shaped as shown in Figs. 1 and 2 with a plurality of fins 11 and at the base thereof with a cylindrical hollow portion 12 constituting the water reservoir.

Water is fed into the reservoir 12 through the

2

conduit 13 formed in a nipple 14 cast integrally with the element 10. Attached to the nipple 14 is a flexible connection 15 preferably of rubber, which is attached at the other end to a metal connection 16 which in turn is connected preferably by a flexible connection with the cooling system for the internal combustion engine so that water is constantly maintained in the water reservoir 12.

10 The element 10 rests upon a felt or rubber ring 17 which in turn rests upon the annular metal base 18. The inner periphery 19 of the base 18 is turned downwardly and to this is secured, preferably by spot welding, a clamp and 15 clamp-bolt assembly 20 which is provided for connecting the cleaner and humidifier assembly with a conduit leading to the intake side of the carburetor.

The base 18 may be provided with grooves such 20 as 21 for strengthening purposes. The outer periphery of the base 18 is also turned downwardly as shown at 22 and to this is secured in any desired way preferably by spot welding the annular oil container 23. The oil container 23 at 25 its upper interior side is provided with a flange 24 to prevent splashing of the oil 25 in the container. At the interior side of the outer side of the container 23 there is provided a supporting elbow 26 which may be spot welded to the wall of the container 23.

26 Resting upon the supporting elbow 26 is the air filter 27. The air filter is formed as a ring shaped container with an interior imperforate metallic wall 28 which is secured by a flange 29 at the upper portion thereof to the exterior peripheral wall 30 of the air filter. The exterior wall 30 is provided with perforations 31 and at the bottom is curved to form the bottom wall 32 of the air filter which is also perforated as shown at 33. The bottom wall 32 of the air filter is provided with an upwardly extending flange 34 which is secured to the lower portion of the interior wall 28 as shown. With the construction described the air enters through the perforations 31, passes through the filter-forming material 35 such as copper filings, glass wool or the like and then leaves the air filter 27 through the openings 33 at the bottom thereof. Upon leaving the air filter 27 through the openings 33 the air comes in contact with the upper surface of the oil 25 where it is further cleansed.

35 Positioned upon the top of the humidifying element 10 is a rubber washer 36 and supported thereon is a metallic ring-shaped element 37 of metal which acts as a silencer. The silencer 37 is provided at its upper portion with a circular

50 55

seat 38 upon which rests a spider 39. A cover 40 preferably constructed of aluminum is positioned above the spider 39 and frictionally engages at its lower edge 41 with the top portion of the air filter 27. Extending through the central portion of the cover 40 and the spider 39 is a clamping rod 42 having a hook 43 at the lower end thereof which engages the bail 44 whose ends 45 engage in openings provided in the upper portion of the clamp and clamp-bolt assembly 20. A nut 46 is secured to the clamping rod 42 supporting the yoke 39 and nuts 47 also on the rod 42 space the cover 40 from the yoke 39. A wing nut 48 threaded upon the rod 42 secures the entire assembly together.

When the cleansed air leaves the surface of the oil 25 it passes upwardly and contacts the exterior surface of the fins 11. Due to the moisture upon such fins a further cleansing action takes place with respect to the air and such cleansing action is continued as the air reverses its direction at the top of the element 10 and passes downwardly through the Venturi shaped opening 49 provided in the element 10 on its way to the carburetor.

During the passage of the air first across the exterior wall of the element 10 and then through the interior conduit 49 the air entrains from the enlarged fin construction an increased quantity of water. It has been found in actual practice that substantially 300% increase is secured in the water content of the air by the construction described above that in usual humidifiers and also due to the enlarged surface an improved cleansing action is also obtained.

If desired the water reservoir 12 may be connected in circuit with the water system of the engine but it has been found that generally this is not necessary and one connection as shown is sufficient.

The pipe 16 is supported in the cover 40 by means of an eyelet 50 of any desired material.

It is believed that the operation of the humidifier and cleanser is evident from the above description and also that in order to replace or cleanse any portions thereof it is only necessary to remove the wing nut 48 and lift up the cover 40. The entire assembly is then easy of access.

The form of the invention shown in Fig. 3 and 4 will now be described.

In this modification the oil bath assisting in the cleansing of the air is eliminated. The humidifying and cleansing element 10 is similar in construction to that above described and the same applies to the various elements having the same reference characters.

However, the base 58 supporting the structure is of ring shape and extends sufficiently to support the air filtering element 59 in addition to the washer 60 upon which the element 10 is supported. The filtering element 59 is formed by two concentric plates 61 and 62. The plate 61 is provided with perforations 63 and the interior plate 62 is provided with perforations 64 while between the two plates 61 and 62 there is placed the filter material such as copper filings, glass wool or the like, 65. The cover 66 in this modification is provided at the interior with an angle plate 67 whose upwardly extending leg is secured to the cover 66 in any desired way such as by rivets 68. The horizontal leg 69 extending towards the interior closes the upper end of the filtering element 59.

Connected to the nipple 14 is a flexible conduit 70 which is connected in turn to the verti-

cally disposed connection 73 passing through an opening 71 provided in the base 58 wherein is disposed a bushing 72. The connection 73 is connected by any desired means to the water system of the internal combustion engine.

The inner plate 62 of the air filter is provided with a recessed portion 74, shown in Fig. 4, for accommodating the connection 73 and the conduit 70.

Also the base plate 58 is provided with struck up resilient tongues 75 for accurately centering the element 10 upon the base member 58.

The operation of the modification described above is similar to that of the first modification described except that the air as it enters from outside the air filter 59 through the openings 63 passes directly therethrough and escapes through the openings 64 and then contacts the fins 11 before reversing its direction and passing through the Venturi central opening of the element 10.

In this case also by removing the wing nut 48 the cover 66 may be removed and this allows all of the interior elements to be replaced or cleaned easily.

25 I claim:

1. A humidifier an air filter for the air-intake of an internal combustion engine comprising a support, an annular water reservoir on said support of porous material having an inner wall of 30 Venturi configuration for enhanced suction action and an outer wall with fins for increased humidifying and cleansing action, an annular oil tank secured to said support for oil to cleanse the air coming into contact with the upper surface 35 thereof, an annular filtering element mounted on said tank and a cover enclosing said reservoir mounted on said filtering element.
2. A humidifier and air filter for the air-intake 40 of an internal combustion engine comprising a support, an annular water reservoir on said support of porous material having an inner wall of Venturi configuration for enhanced suction action and an outer wall with fins for increased 45 humidifying and cleansing action, an annular oil tank secured to said support for oil to cleanse the air coming into contact with the upper surface thereof, an annular filtering element mounted on said tank, a clamping member secured to said support for mounting the humidifier upon a conduit leading to the carburetor air intake, a bail 50 secured to said clamping member, a silencer mounted on the top of said reservoir, a cross bar seated on said silencer, a cover mounted on said filtering element, a rod secured to said bail and 55 extending through said cross bar and cover and a wing nut on said rod securing the assembly together.

ANTOINE GAZDA.
